US00D549388S

(12) **United States Design Patent**
Lehman et al.

(10) **Patent No.:** US D549,388 S
(45) **Date of Patent:** ** Aug. 21, 2007

(54) **TRACK ADAPTOR**

(75) Inventors: **Gregg Lehman**, Peachtree City, GA (US); **Paul Bartlett**, Newnan, GA (US); **Vincent Iacovelli**, Newnan, GA (US)

(73) Assignee: **Cooper Technologies Company**, Houston, TX (US)

(**) Term: **14 Years**

(21) Appl. No.: **29/252,117**

(22) Filed: **Jan. 19, 2006**

Related U.S. Application Data

(63) Continuation of application No. 29/233,364, filed on Jun. 30, 2005.

(51) **LOC (8) Cl.** 26-99

(52) **U.S. Cl.** D26/139

(58) **Field of Classification Search** D26/138, D26/24, 63, 26, 72, 113, 118, 137, 153, 155; D13/133; D23/209; 439/207; 362/147, 362/269, 371, 249, 294, 119, 391, 382, 404, 362/257, 407, 648

CLAIM

The ornamental design for a track adaptor, as shown and described.

DESCRIPTION

This application is related to co-pending applications: Ser. No. 11/322,837, filed Dec. 30, 2005 and titled “Halo Flex Track”; Ser. No. 11/324,099, filed Dec. 30, 2005 and titled “Halo Power Supplies”; Ser. No. 11/323,231, filed Dec. 30, 2005 and titled “Halo Clam Shell Connections”; and Ser. No. 11/323,755, filed Dec. 30, 2005 and titled “Halo Hubs and Connections”.

FIG. 1 is a top, front perspective view of a first embodiment of a track adaptor showing our new design;

FIG. 2 is a bottom, side perspective view thereof;

FIG. 3 is a left side view thereof, the right side view being a mirror image;

FIG. 4 is a top, front perspective view of a second embodiment of a track adaptor showing our new design;

FIG. 5 is a bottom, side perspective view thereof; and,

FIG. 6 is a left side view thereof, the right side view being a mirror image.

The broken lines form no part of the claimed design.
